UNITED STATES PATENT OFFICE.

CHARLES W. KIRSCH, OF STURGIS, MICHIGAN.

CURTAIN ROD AND BRACKET.

Application filed January 27, 1923. Serial No. 615,223.

To all whom it may concern:

Be it known that I, CHARLES W. KIRSCH, a citizen of the United States, residing at Sturgis, in the county of St. Joseph and

5 State of Michigan, have invented certain new and useful Improvements in Curtain Rods and Brackets, of which the following is a specification.

This invention has for its object to provide certain new and useful improvements in curtain and drapery rods and particularly of the two-piece extensible telescope type which are very commonly used and which have their respectively opposite ends of different 5 sizes in transverse sectional dimensions.

The particular object of the present invention is to provide brackets for engaging and supporting the curtain rods in their normal positions on window frames which 10 will not only firmly support said rods in a horizontal position but will also hold them so firmly in position as to prevent their being accidentally disengaged from the brackets by accidental pulls and sudden releases 15 of curtains or draperies suspended from said rods and causing the spring of the rods which may effect their accidental release.

The present invention operates on substantially the same principle and embodies 20 more or less the feature or features of the invention described and claimed in my co-pending application for Letters Patent filed the 23rd day of November, 1922, Serial No. 602,904.

25 The present invention is illustrated in its preferred embodiment in the accompanying drawings, in which—

Fig. 1 is a top plan view of a curtain rod of the general type referred to suitably 30 engaged with and supported by its brackets;

Fig. 2 is a detail transverse section of same on the line 2—2 of Fig. 1;

Fig. 3 is a vertical section on the line 3—3 of Fig. 1;

Fig. 4 is a view similar to Fig. 3, showing the position of the curtain rod preparatory to its position as shown in Fig. 3 when being mounted on its brackets; and

Fig. 5 is a detail section on the line 5—5 of Fig. 3.

While I have illustrated in the accompanying drawings a two-piece telescopic curtain rod of the type that is generally referred to as C-shaped in cross-section, it 5 will be understood that the invention is applicable to hollow curtain rods of any so-

called tubular telescopic types, the illustration of the C-shape being chosen because it has become the most popular on the market.

60 By reference to Figs. 1 and 2, it will be seen that the two members A and B of the rod are of different cross-sectional dimensions, the portion A, which might be referred to as the female member, being of a size 65 adapted to readily telescopically receive what might be termed the male member B. Both members A and B are provided in their respective end portions with perforations C in their top and bottom edges, 70 by means of which said members may be engaged with the brackets therefor, the said end portions of said rods containing said perforations extending at substantially right-angles to the main or middle portion 75 of said members A and B which are telescopically engaged with each other.

The brackets consist preferably of wall plates D from which a vertical fin or flange E projects, the latter being equipped at its 80 upper end with a projection F adapted to engage in a perforation C and constituting what might be termed a hook from which the rod is suspended. The perforation C is so disposed relatively to the extreme end of 85 the curtain rod member, as to leave metal between the said extreme end and the nearest adjacent wall perforation equal, or substantially equal, in length to the distance between the vertical edge of said projection 90 F opposing the plate D and the face of said plate. The ends of the members A and B being cut off square, that is, perpendicularly to the longitudinal wall thereof, it will be obvious that said edge when the members 95 are engaged with the fin E will abut snugly against the plate D with its lower end portion bearing against said plate, whereas the wall engaged with the projection F will be more or less suspended from said projection, 100 the rod being thus adapted to be held so that its arms project perpendicularly from the face of the plate D.

105 It is desirable to provide means whereby the rods may be so firmly engaged with its supporting brackets as to prevent any rattling thereof or any accidental disengagement of the same from the brackets by a flection of the rods by a pull on the curtains and a sudden release of such flection which, 110 in some instances, may cause the rods to spring upwardly to substantially the posi-

tion shown in Fig. 4, and such flexion may further cause a disengagement of the projection F from the perforation through which it is passed, thus causing the rod to be disengaged from one or both its supporting brackets. Strong drafts may sometimes also effect some vibration of the rod and this might be annoying.

The present invention therefore consists more particularly in so forming and providing dimensions of the fin E of the brackets as to cause the lower end thereof to firmly engage the wall of the bracket opposing that containing the perforation in which the projection F is engaged so as to hold said rod very firmly in position. Preferably the fin E is provided at its lower end with a rounded projection G which is so spaced from the wall plate B as to engage in the perforation C in the lower edge of the rod when the latter is brought from the position shown in Fig. 4 to that shown in Fig. 3. The position shown in Fig. 4 is that which is substantially normally required to effect engagement of the projection F in the perforation or openings C in the upper edge of the rod, whereupon it may be readily swung to the position shown in Fig. 3, but during such swing the lower wall of the rod will be flexed with respect to the upper wall thereof to spring over said projection E. It will be understood of course that it is not essential for the projection G to engage in the perforation, as a mere flexing of the lower wall with respect to the upper wall of the rods as aforesaid will accomplish the purpose satisfactorily, but by reason of the presence of the perforation necessary to permit the positions of the members A and B to be reversed with respect to the two wall plates, advantage thereof may be taken to secure a somewhat better effect from the standpoint of rigidity of position of the rods with respect to the window casing than would otherwise be the case.

The depth of the fin E must be such that it will firmly engage in the female member A of the rod and also, and of course still more firmly, engage in the end of the male portion B of the rod, the upper and lower walls of the latter being flexed to a greater degree than those of the member A in effecting engagement of the rod with its brackets, as will be obvious.

It will be apparent that in its broader aspects, the brackets illustrated and described herein, each disclose a supporting projection for engaging in the upper perforation of the rod, and another projection for engaging in the lower perforation of the rod. The last-mentioned projection functions not only as above specifically described but also to prevent a pivotal movement of the arm of the rod, when only one of the two arms thereof is engaged with its bracket as sometimes occurs

when the rod is being mounted by an individual on a window-casing of a width too great to permit both arms to be readily simultaneously engaged with both brackets. In such case the one arm engaged with its bracket is subjected to a tortional strain which, except where other than light lace or similar curtains are suspended from the rod, will not be permanently distorted owing to the resiliency of the metal. This function of the fin or flange of the bracket is disclosed in my Patent No. 1,187,914 (page 2, lines 7 to 37 inclusive) which does not, however, disclose a projection for engaging in the lower perforation. Thus, the lower projection coacts with the lower perforation to prevent pivotal movement of the rod relatively to its bracket in one direction, as last above described, and to resist and prevent, respectively, such a movement of the rod relatively to either or both its brackets as would tend to effect its disengagement from the latter.

I claim as my invention:

1. A curtain rod including two substantially parallel, open ended arms adapted to be supported in a horizontal plane, wall brackets adapted to be engaged with the free ends of said arms, the latter and said brackets equipped with inter-engaging formations above and below the horizontal axis of said arms whereby to effect suspension of said arms from the brackets at points in the top wall portions of said free ends of said arms, said inter-engaging formations adapted to permit a pivotal movement of said arms from a horizontal position upwardly to effect disengagement from, and vice versa to effect engagement with said brackets, said means on said brackets interchangeably engageable with the formations of both said arms, the inter-engagement of the lower formations of said arms and brackets when the latter are horizontally disposed serving to hold said arms firmly in said horizontal position and yieldably resisting free initial pivotal movement thereof from their normal horizontal position to effect disengagement as aforesaid.

2. The combination with a curtain rod member including an arm adapted to be normally supported to project horizontally outwardly from and perpendicularly to the face of a window-casing or the like, said arm open at the end opposed to said face and having perforations in the uppermost and lowermost portions of its wall, respectively, adjacent said open end, a supporting device for said arm including a surface portion against which the open end of said arm is adapted to abut when in its normal position, a hook element adapted to engage in the upper perforation for supporting said arm and maintaining it normally abutted against said surface portion, said arm

- 5 pivotally movable on said hook element in a vertical plane relatively to the said device through an arc upwardly from its normal position, and a projection adapted to enter the open end of said arm and engage in the lower perforation for yieldably resisting pivotal movement of said arm and preventing disengagement thereof from said hook when in its normal position.
- 10 3. A curtain fixture including a rod terminating in open-ended arms, each provided with perforations in its upper and lower wall portions, respectively, contiguous to the free ends of said arms, and supporting brackets for said arms, each comprising a wall plate against which the open ends of said arms are adapted to abut, a flange on said plate equipped at its upper end with a projection adapted to engage in the upper perforation of the arm and co-acting with said plate to effect suspension and support of said arm perpendicularly of said plate and permitting pivotal movement of the same relatively to the plate, and a rounded projection at the lower end of said flange adapted to effect temporary expansion of the open end of the arm as the latter is swung to or from its normal perpendicular position relatively to said plate and engage in said lower perforation as said arm contracts upon attaining said normal position, to thereby latch said arm to said bracket.
- 15 4. A curtain fixture including a substantially tubular rod terminating in substantially parallel open ended arms each provided in its uppermost wall portion contiguous to its open end with a perforation, a wall bracket for each arm equipped with a projecting hook for engaging in said perforation for supporting said arm, and in terengaging latch formations on said arm and said bracket disposed below said hook and perforation for firmly but yieldably holding said rod and bracket against relative movement on said hook and perforation as a fulcrum.
- 20 5. A curtain fixture including a hollow curtain-rod having open ends, there being perforations in the upper and lower walls of said rod contiguous to said open ends, and supporting brackets for said rod including wall-plates each equipped with projections, one of the latter adapted to engage in the perforation in the upper wall of the rod for supporting the same and preventing movement thereof away from the wall plate, and the other thereof adapted to engage in the perforation in the lower wall for resisting pivotal or disengaging movement of said rod relatively to said rod-supporting projection.
- 25 6. A curtain fixture including a hollow curtain rod terminating in substantially parallel open-ended arms extending substantially perpendicularly to the middle portion thereof and provided in its upper and lower wall portions, contiguous to the ends of said arms, with perforations, and supporting brackets for said rod including wall-plates, projections thereon including a pair for engaging in the upper perforations and coacting with the wall-plates to effect support of the rod, and another pair of projections for engaging in the lower perforations, to thereby effect support of each arm of the rod independently of the other for preventing lateral pivotal movement of the rod with respect to the bracket when only one end of the rod is engaged with its bracket.
- 30 7. A curtain fixture including a hollow curtain rod terminating in substantially parallel open-ended arms extending substantially perpendicularly to the middle portion thereof and provided in its upper and lower wall portions, contiguous to the ends of said arms, with perforations, and supporting brackets for said rod including wall-plates, projections thereon including a pair for engaging in the upper perforations and coacting with the wall-plates to effect support of the rod, and another pair of projections for engaging in the lower perforations, to thereby effect support of each arm of the rod independently of the other for preventing lateral pivotal movement of the rod with respect to the bracket when only one end of the rod is engaged with its bracket.
- 35 8. A curtain fixture including a hollow curtain rod terminating in substantially parallel open-ended arms extending substantially perpendicularly to the middle portion thereof and provided in its upper and lower wall portions, contiguous to the ends of said arms, with perforations, and supporting brackets for said rod including wall-plates, projections thereon including a pair for engaging in the upper perforations and coacting with the wall-plates to effect support of the rod, and another pair of projections for engaging in the lower perforations, to thereby effect support of each arm of the rod independently of the other for preventing lateral pivotal movement of the rod with respect to the bracket when only one end of the rod is engaged with its bracket.
- 40 9. A curtain fixture including a hollow curtain rod terminating in substantially parallel open-ended arms extending substantially perpendicularly to the middle portion thereof and provided in its upper and lower wall portions, contiguous to the ends of said arms, with perforations, and supporting brackets for said rod including wall-plates, projections thereon including a pair for engaging in the upper perforations and coacting with the wall-plates to effect support of the rod, and another pair of projections for engaging in the lower perforations, to thereby effect support of each arm of the rod independently of the other for preventing lateral pivotal movement of the rod with respect to the bracket when only one end of the rod is engaged with its bracket.

CHARLES W. KIRSCH.
